(57) **CLAIM**

I claim the ornamental design for a rotating wash brush, as shown and described.

DESCRIPTION

FIG. 1 is a top plan view of my design for a rotating wash brush;

FIG. 2 is a rear elevation view thereof;

FIG. 3 is a right, front perspective view thereof;

FIG. 4 is a left, front perspective view thereof;

FIG. 5 is a right, side elevation view thereof;

FIG. 6 is a left, side elevation view thereof;

FIG. 7 is a bottom plan view thereof; and,

FIG. 8 is front elevation view thereof.

The broken lines in the figures illustrate portions of the rotating wash brush that form no part of the claimed design.
